Inventor:

UNITED STATES PATENT OFFICE.

CHARLES H. MUCKENHIRN, OF DETROIT, MICHIGAN, ASSIGNOR TO THE STANDARD SANITARY MANUFACTURING COMPANY, OF PITTSBURGH, PENNSYLVANIA, A CORPORATION OF NEW JERSEY.

SUPPORTING MEANS FOR CLOSET-BOWLS.

1,165,016.

Specification of Letters Patent. Patented Dec. 21, 1915.

Application filed September 15, 1915. Serial No. 50,851.

To all whom it may concern:

Be it known that I, CHARLES H. MUCKENHIRN, a citizen of the United States, residing at Detroit, in the county of Wayne and State of Michigan, have invented certain new and useful Improvements in Supporting Means for Closet-Bowls, of which the following is a specification, reference being had therein to the accompanying drawing.

10 This invention relates to an improvement in supporting means for lavatory basins, closet bowls and the like.

Heretofore it has been the practice to support a closet bowl at the side of the room free of the floor and usually by suitable attachments from the stand-pipe. In certain building structures it is somewhat objectionable to employ the stand-pipe for the bowl support in that there is liability of 20 movement of the pipe with relation to the walls and instability of the general support.

The present invention relates to an independently positioned support for the bowl formed within the space between the walls, 25 or adjacent the stand-pipe, wholly disassociated from the stand-pipe, but provided with means constituting a rigid carrier for the bowl and its attaching means.

In the accompanying drawings a preferred embodiment of the invention is shown but it is to be understood that various changes may be made without departing from the nature and principle of the invention.

35 Figure 1 is a detail side elevation of the improvement showing parts of the equipment in section; and Fig. 2 is a rear elevation of the improvement.

Side supported bowls are usually so connected with the supporting element back of the partitions, or wall, that the bowl is carried independent of the partition or wall. To support the weight of the members fixedly and securely I provide a device comprising a cast or otherwise formed metallic 45 standard A having a foot member B projecting forwardly to a plane below the bowl C. This foot member is conveniently em-

bedded in the concrete floor, but may be secured in any desired manner depending upon the character of the floor structure. The upper end of the standard A is formed with a forwardly projecting supporting flange D conveniently of circular formation in cross section. This flange is an integral part of the standard and its open center coincides with a similar opening in the top of the standard. When in position the circular flange of the standard is in line with the closet bowl discharge and the nipple or branch E leading from the stand-pipe passes freely through the said opening in the standard and flange.

Sleeved on the circular flange D is a clamping member F having forwardly projecting arms F' with which the bowl securing bolts G engage. There is interposed between the ends of the arms and the bowl flange suitable adjusting bushings H, these features, however, are not of my invention. 70 The present invention relates to the standard and is employed in the combination with the bowl supporting means which is adjustably secured on the standard. The adjustability of the sleeve on the circular flange is effected by the means of splitting the sleeve at one side and providing it with perforated lugs g through which a suitable threaded bolt passes which is capped by a nut. By this means the sleeve may be adjusted backward and forward on the flange as well as around the flange so as to properly position the arms with relation to the bowl attachments. The standard B is conveniently reinforced by a vertical rib a and constitutes a very rigid support for the bowl, the extension of the foot of the standard beneath the bowl is obviously for the purpose of centering the support substantially below the weight which it carries. By making the opening in the flange and in the ends of the standards somewhat larger than the nipple considerable latitude is permitted in the adjustment of the nipple to the bowl so that exactness of fit is not required.

95 As stated, it is to be understood that

minor changes and alterations may be made without departing from the spirit of the invention.

Having thus described my invention what I claim is:

The combination with a fixedly positioned standard having an opening at its upper end, and a forwardly projecting circular flange, of a nipple passing through the open-

ing and flange, a bowl and means for securing the bowl to the standard comprising an attaching part secured to said flange.

In testimony whereof I hereunto affix my signature in the presence of two witnesses.

CHARLES H. MUCKENHIRN.
